UNITED STATES PATENT OFFICE.

HENRY CRIGLER, OF FRANKLIN, WEST VIRGINIA, ASSIGNOR OF ONE-HALF
TO MASON BOGGS, OF SAME PLACE.

DESIGN FOR A CLAMP MEMBER.

SPECIFICATION forming part of Design No. 31,082, dated June 27, 1899.

Application filed May 29, 1899. Serial No. 718,750. Term of patent 14 years.

To all whom it may concern:

Be it known that I, HENRY CRIGLER, a citizen of the United States, residing at Franklin, in the county of Pendleton and State of West Virginia, have invented and produced a new and original Design for a Clamp Member, of which the following is a specification.

This invention relates to a new and original design for a clamp member.

10 The leading feature of the design resides in the body having the approximately-rectangular flat shank, provided at one end with an extended concavo-convex jaw portion rounded at the side and end edges thereof and having at the outer side edge of its concavity a substantially flat lip disposed longitudinally of the jaw.

15 A minor feature of the design resides in the jaw portion of the body being provided upon the outer convexed side thereof with a continuous offset marginal rib or bead extending around the end and outer side edges of said jaw portion.

20 In the drawings, Figure 1 is a perspective view of a clamp member embodying the design contemplated by the present invention. Fig. 2 is a similar view showing the inner or concaved side of the jaw portion of the body. Fig. 3 is a central longitudinal sectional view 25 of the clamp member embodying the design.

30 Referring to the drawings, the numeral 1 designates the flat body of the member, which is provided with an approximately-rectangu-

lar flat shank 2. The flat shank 2 of the body is provided with straight edges and has extended from one end thereof the concavo-convex jaw portion 3 of the body. This jaw portion 3 forms an integral part of the shank 2 and is of a greater width than the latter, the end edges of said jaw portion merging on curved 40 lines into the straight side edges of the said flat shank.

The concavo-convex jaw portion 3 of the body has the outer convexed side 5 thereof deflected at one side of the plane of the flat 45 shank 2, and upon its outer convexed side the said jaw portion 3 is provided with a continuous offset marginal rib or bead 4, extending around the opposite end and outer side edges thereof. All of the edges of the concavo-convex jaw portion 3 are rounded, and said jaw portion is further provided at the outer side edge of its concavity with a substantially flat lip 6, disposed longitudinally thereof.

55 What is claimed is—

The design for a clamp member herein shown and described.

In testimony that I claim the foregoing as my own I have hereto affixed my signature in 60 the presence of two witnesses.

HENRY CRIGLER.

Witnesses:

B. S. HAMMER,
WILLIAM MCCOY.
